United States Patent Office

Des. 208,120
Patented July 18, 1967

208,120

KEYBOARD PRINTER

Henry Dreyfuss, South Pasadena, Calif., and Donald M. Genaro, Haworth, N.J., assignors to Teletype Corporation, Skokie, Ill., a corporation of Delaware

Filed Oct. 10, 1966, Ser. No. 4,225

Term of patent 14 years

(Cl. D64—11)

FIG. 1

FIG. 2

FIG. 3

FIG. 4

FIG. 1 is a front perspective view of a keyboard printer showing our new design;

FIG. 2 is a right side view thereof;

FIG. 3 is a front view thereof; and

FIG. 4 is a rear perspective view thereof.

The dominant features of our design are shown in full lines.

We claim:

The ornamental design for a keyboard printer, substantially as shown and described.
